DRAPEY HOOK

Eva C. Swanson, Detroit, Mich., assignor to
Ethel Swanson, Detroit, Mich.

Application June 23, 1944, Serial No. 541,809

3 Claims. (Cl. 24—86)

1

This invention relates to drapery hooks and more particularly to such hooks adapted to suspend draperies or the like from a suitable supporting rod.

A primary object of this invention is the provision of an improved drapery hook which will securely hold a drapery or the like in suspended relation from a desired support.

An additional object is the provision of a drapery hook which may be secured to the drapery in such manner as to provide a heading, or portion thereof extending upwardly above the supporting means to conceal the same.

A still further object is the provision of such a drapery hook which may be readily adjusted to provide a variety of different heights of headings, without varying the point on the drapery to which the hook is secured.

Additional objects reside in the provision of a drapery hook which may be readily and easily attached to a drapery, which will securely hold the drapery in the desired position, which will be durable in construction, and which may be simply and cheaply manufactured.

Still further objects reside in the combinations of elements, arrangements of parts and features of construction, all as will be more fully pointed out hereinafter and shown in the accompanying drawing wherein there is disclosed a preferred embodiment of this inventive concept.

In the drawing:

Figure 1 is a perspective view of a portion of the drapery hook shown in open position.

Figure 2 is a view similar to Figure 1 but showing the device in closed or drapery holding position.

Figure 3 is a side elevational view of an additional part of the drapery hook.

Figure 4 is a side elevational view disclosing the drapery hook as applied to a drapery (shown in section), a supporting portion for the hook being shown in position prior to final adjustment.

Figure 5 is a view similar to Figure 4 disclosing parts after the assembly is completed and the drapery suspended from a curtain rod or the like (indicated in dotted lines) and

Figure 6 is a top plan view of the pin securing means comprising a portion of the device as shown in Figures 1 and 2.

Like reference numerals refer to like parts throughout the several views of the drawing.

Referring now to the drawing the drapery hook is comprised of a drapery engaging pin, generally indicated at 10, comprised of a single sheet metal stamping or the like, including a relatively flat,

2

rectangular plate 11 tapering to a pin 12 which terminates in a needle point 13, pin 12 being bent upwardly with respect to portions 11 as at 14 and the resiliency of the metal normally tending to bias the parts to open position as shown in Figure 1. The upper extremity of portion 11 is bent inwardly toward point 13, as indicated at 15 and cut out to form a recess or aperture 16 (see Figure 6), a projection 17 being provided securely to hold point 13 in locked relation within recess 16 when the pin is closed, as shown in Figure 2. Rectangular portion 11 is likewise provided with a plurality of apertures 18a, 18b and 18c cut therethrough, preferably of rectangular configuration, adapted to engage a supporting hook generally indicated at 20 (see Figure 3). Hook 20 which may be of heavy gauge wire, or a similar material, is comprised of a U-shaped portion 21 adapted to be engaged with a curtain rod or the like, one leg of which 21a is elongated and curved upwardly as at 22 to provide an upwardly extending portion 23 terminating at a point above the base of the U in an inwardly curved needle point 24.

25 The method of use of the device should now be readily understandable. Having particular reference to Figures 4 and 5 point 13 of pin 10 is inserted through the lining 25 of a drapery 26 at a desired point, and then passed outwardly at 30 a second point above the first-mentioned point and hooked behind projection 17 in recess 16, thus securely fastening the pin to the drapery. Obviously, in the case of unlined draperies the pin may be passed through the material of the drapery itself. Point 24 is then passed inwardly through a selected aperture, as, for example, 18b and through the portion of the drapery between the upper and lower points of insertion of pin 12 (see Figure 4). Point 24 is then passed outwardly through the lining of the drapery and, due to its above-mentioned curved configuration, 40 abuts and is seated against the interior of rectangular portion 11, thus forming a relatively firm support for hook 20, which is then placed in 45 position above a supporting curtain rod or bar 27.

It will now be apparent that the height of the heading, that is, the portion of the drapery extending above supporting rod 27 is determined by the aperture in which hook 20 is inserted. It will also be seen that the device may be constructed in any desired length and provided with any suitable number of apertures therethrough to provide for headings of many different heights.

While only one hook has been herein shown and 55 described, it will be understood that a plurality

of drapery hooks may be suitably aligned along a drapery, the number utilized being dependent on the width of the drapery and the amount of space desired therebetween.

From the foregoing it will now be seen that there is herein provided a drapery hook accomplishing all the objects of this invention and others including many advantages of great practical utility and commercial importance.

As many embodiments may be made of this inventive concept and as many modifications may be made in the embodiment hereinbefore described and shown in the accompanying drawing, it is to be understood that all matter herein is to be interpreted merely as illustrative and not in a limiting sense.

I claim:

1. A drapery hanger comprising a base having a series of longitudinally spaced apertures, a hook having supporting means and an attaching arm insertable through a pair of adjacent apertures of said base, said attaching arm having a straight portion and a pointed extremity extending at an angle to said straight portion, said extremity extending into one of said apertures in said base, through said drape at two points and projecting outwardly through an adjacent aperture in said base.

2. The combination of claim 1 wherein said hook is S-shaped.

3. A drapery hanger comprising a base having a series of longitudinally spaced apertures, a hook having supporting means and an attaching arm insertable through a pair of adjacent apertures of said base, said attaching arm having a straight portion and a pointed extremity inclined back towards the base and extending into one of said apertures in said base, through said drape at two points and projecting outwardly through an adjacent aperture in said base.

EVA C. SWANSON.
